FIRING MECHANISM INCLUDING A UNITARY SPRING WITH THREE ARMS

Louis Elkas, Agawam, and Thomas J. Davies, Springfield, Mass., assignors to Emhart Corporation, a corporation of Connecticut

Filed Sept. 19, 1963, Ser. No. 309,991
 5 Claims. (Cl. 42—69)

The present invention relates to improvements in firing mechanisms for rifles and the like.

The object of the invention is to simplify and reduce the number of parts as well as the manufacturing cost of firing mechanisms employed in rifles and other firearms.

In broad terms, these ends are obtained by employing in a rifle construction, a single multi-purpose spring which serves to operate the trigger, the sear and the hammer.

The above and other related objects and features of the invention will be apparent from a reading of the following description of the disclosure found in the accompanying drawing and the novelty thereof pointed out in the appended claims.

In the drawing:

FIG. 1 is a fragmentary view of a rifle with portions broken away to show a firing mechanism embodying the present invention, which is in a cocked position;

FIG. 2 illustrates the firing mechanism in its fired position;

FIG. 3 illustrates the firing mechanism in a position ready to be cocked;

FIG. 4 is a perspective view of the firing mechanism in its cocked position; and

FIG. 5 is a perspective view of the multi-purpose spring employed in the firing mechanism.

FIG. 1 shows the central portion of a rifle R comprising a chamber c having a bolt b slidable therein and moved in a known manner, as by a manually operated lever. The rifle also comprises a conventional stock s which may be slotted to receive a firing mechanism housing 10 having a trigger guard 12 formed integrally therewith.

The firing mechanism comprises a hammer 14 which is pivotally mounted on a pin 16. The pin 16 is supported at its opposite ends by vertical walls 18 of the housing 10 (the front wall 18 is broken away in the drawing). A sear 20 is pivotally mounted on a pin 22 which is also supported at its opposite ends by the housing walls 18. A trigger 24 is also pivotally mounted on the pin 22. The trigger 24 comprises upwardly extending legs 26, 28 (FIGS. 2 and 4) which embrace the sear 20 and receive the pin 22.

The forward end of the sear 20 is adapted to be received in a notch 30 formed in the lower end of the hammer 14 to hold the latter in a cocked position. The rear portion of the sear 20 overlies an extension 32 of the trigger leg 28 which is bent to this relationship.

A single multi-purpose spring 34, illustrated in an unflexed condition in FIG. 5, exerts spring pressures on the hammer 14, sear 20 and trigger 24. Starting with an arm 36 which engages the trigger leg 28 at a point rearwardly of its pivotal axis, this spring is then coiled around the pin 16. It next is formed as an inverted loop 38 which engages the rear surface of the hammer 14 adjacent its upper end. Next the spring is again coiled about the pin 16 on the opposite side of the hammer 14. The spring 34 then terminates in an arm 40 having an inturned end which engages the upper surface of the sear 20 also rearwardly of its pivotal axis. It will be seen that a small lug 42 (FIG. 4) projects from the sear 20 to hold the spring arms 36 and 40 in spaced relation insuring that arm 36 will bear against the trigger leg 28.

In the cocked position of the firing mechanism (FIG. 1)

the spring 34 is deflected so that the arm 36, through engagement with the trigger leg 28, maintains the trigger 24 in a position determined by engagement of the extension 32 with the lower wall of the housing 10, which serves as a stop means for the clockwise pivoting of the trigger. The spring arm 40 bears against the rear end of the sear to maintain its forward end in engagement with the notch 30 to hold the hammer 14 in its cocked position. Deflection of spring loop 38 provides stored energy which is released to strike the firing pin of the bolt b when the trigger is operated.

The trigger is operated by moving first against the pressure of spring arms 36 until the extension 32 rotates into engagement with the downwardly extending lug 41 at the rear end of the sear. Thereafter the trigger and sear are rotated together counterclockwise against the pressure of spring arms 36 and 40 until the forward end of the sear is swung out of the notch 30. The spring loop 38 will then cause the hammer 14 to forcibly strike the firing pin of the bolt b and fire the round in the chamber c.

Normally, after firing, the trigger would be released (FIG. 3) preparatory to recocking the firing mechanism. Spring arm 36 returns the trigger 24 to the position determined by engagement of the extension 32 with the lower wall of the housing 10. Spring arm 40 causes the forward end of the sear to bear against the lower end of the hammer 14. Spring loop 38 maintains the hammer 14 in engagement with the bolt b. The loop 38 and arms 36, 40 are deflected slightly inwardly at all times to maintain the sear and trigger in position for recocking.

To cock the firing mechanism, the bolt b is drawn rearwardly, pivoting the hammer against the action of the spring loop 38 until the forward end of the sear 20 engages the notch 30. The bolt b is then returned to its forward position preparatory to firing another round of ammunition. The various parts are thus brought back to the cocked position described in connection with FIG. 1.

The multi-purpose spring 34 has several advantages. Particularly it will be noted that there are three free ends (36, 38 and 40) each of which serves a different function and yet there is cooperation in that these free ends mutually provide "anchors" for spring controlled operation of the hammer, sear and trigger. Previously separate notches or the like were provided in the firing mechanism housing for anchoring one end or leg of the operating spring.

Other advantages will be apparent in that the number of parts is reduced with a consequent reduction in assembly and inventory costs.

Having thus described the invention, what is claimed as novel and desired to be secured by Letters Patent of the United States is:

1. Firing mechanism for a rifle or the like having a reciprocable bolt, said mechanism comprising a housing generally underlying said bolt and having opposed walls, a hammer pin supported at its opposite ends by said housing walls, a hammer pivotally mounted on said hammer pin and engageable with said bolt to discharge the rifle, a trigger pin supported at its opposite ends by said housing walls, a trigger depending from said housing and having upturned spaced legs pivotally receiving said trigger pin, said housing having a lower wall and one of said trigger legs having an extension engageable therewith, a sear also pivotally mounted on said trigger pin and disposed between the trigger legs, the rear end of said sear overlying the trigger leg extension, said hammer having a notch formed in its lower end, the forward end of said sear being engageable with said notch to hold the hammer in a cocked position, a multi-purpose spring comprising a loop engaged with the rear surface of said hammer adjacent the outer end thereof, the inner ends of said loop being coiled about said hammer pin and then projecting therefrom as spring arms, one of said

spring arms engaging a trigger leg rearwardly of the trigger pin axis to urge the trigger leg extension into engagement with the lower housing wall, said sear having an elevated portion maintaining this spring arm in engagement with the trigger leg, the other spring arm engaging the rear of said sear and urging the forward end thereof into engagement with the notch in said hammer when it is in its cocked position.

2. Firing mechanism for a rifle or the like having a reciprocable bolt, said mechanism comprising a housing having opposed walls, a hammer pin supported at its opposite ends by said housing walls, a hammer pivotally mounted on said hammer pin and engageable with said bolt to discharge the rifle, a trigger pin supported at its opposite ends by said housing walls, a trigger pivotally mounted on said trigger pin, said housing having a lower wall and said trigger having an extension engageable therewith, a sear also pivotally mounted on said trigger pin, the rear end of said sear overlying said trigger extension, said hammer having a notch formed in its lower end, the forward end of said sear being engageable with said notch to hold the hammer in a cocked position, a multi-purpose spring comprising a loop engaged with the rear surface of said hammer adjacent the outer end thereof, the inner ends of said loop being coiled about said hammer pin and projecting therefrom as spring arms, one of said spring arms engaging the trigger at a point urging the trigger extension into engagement with the lower housing wall, the other spring arm engaging the rear of said sear and urging the forward end thereof into an engagement with the notch of said hammer when it is in its cocked position.

3. Firing mechanism for a rifle or the like having a reciprocable bolt, said means comprising hammer pin, a hammer pivotally mounted on said hammer pin and engageable with said bolt to discharge the rifle, a trigger pin, a trigger pivotally mounted on said trigger pin, stop means for limiting the pivotal movement of said trigger, said trigger having an extension engageable therewith, a sear also pivotally mounted on said trigger pin, said trigger pin having means engageable with said sear to impart pivotal movement thereto, said hammer having a notch formed therein, the forward end of said sear being engageable with said notch to hold the hammer in a cocked position, said sear being pivoted out of said notch in response to movement of said trigger, a multi-purpose spring comprising a loop engaged with the rear surface of said hammer adjacent the outer end thereof,

5 the inner ends of said loop being coiled around said hammer pin and projecting therefrom as spring arms, one of said spring arms engaging the trigger at a point urging the trigger extension into engagement with said stop means, the other spring arm engaging said sear at a point urging the forward end thereof into engagement with the notch of said hammer when it is in its cocked position.

4. Firing mechanism for a rifle or the like, said mechanism comprising a hammer, a sear engageable with said hammer to hold it in cocked position and a trigger engageable with said sear to displace the sear from engagement with the hammer to permit the hammer to fire the rifle, and a multi-purpose spring having three free ends, one of which urges the hammer into firing position, another of which urges the sear into engagement with the hammer and the other of which urges the trigger in a direction counter to that which causes the sear to be displaced from engagement with the hammer, said spring having a configuration whereby maximum spring pressure is applied to the sear and trigger when said hammer is cocked.

5. Firing mechanism for a rifle or the like comprising a pivotable hammer, a trigger, and a sear interengageable with the hammer and trigger for retaining and releasing said hammer from cocked condition in response to trigger actuation, and a unitary spring coiled about the pivot of said hammer and having three arms extending radially therefrom, one of said arms being in the form of a loop engaged with said hammer, said spring including a second arm engaged with said sear and a third arm engaged with the trigger, said second arm urging with maximum spring pressure, said sear into cocking engagement with said hammer when said hammer is cocked and said third arm providing maximum spring pressure on said trigger.
